UNITED STATES PATENT OFFICE

124,145

DESIGN FOR A DRESS OR SIMILAR ARTICLE

Madeleine Croizat, New York, N. Y.

Application September 14, 1940, Serial No. 95,059

Term of patent 3½ years

To the Commissioner of Patents:

Be it known that I, Madeleine Croizat, a citizen of the United States, residing at 353 West 56th St., New York city, in the county of New York and State of New York, have invented a new, original, and ornamental Design for a Dress or Similar Article, of which the following is a specification, reference being had to the accompanying drawing, forming part thereof.

The characteristic feature of my design resides in the combination on the specific dress disclosed of the beads and embroidery arranged around the blouse pockets, in association with the knife-pleated skirt as shown.

I claim:

The ornamental design for a dress or similar article, substantially as shown and described.

MADELEINE CROIZAT.
